TAPE DRIVING SYSTEM FOR MAGNETIC SOUND RECORDING MACHINES AND THE LIKE

Herman S. Heller, West Los Angeles, Donald E. Ross, Eagle Rock, and Forrest J. Lilly, Los Angeles, Calif.; said Ross and said Lilly assignors to said Heller

Application November 19, 1940, Serial No. 366,232

10 Claims. (Cl. 242—55)

This invention relates generally to tape driving systems for magnetic sound recording machines and the like employing record tapes. The invention has been designed primarily as a drive system for the record tape of magnetic sound recording and reproducing machines, and will therefore be disclosed with that application chiefly in view, though without necessary limitation thereto.

The record tape of magnetic sound recording machines is ordinarily fed from a supply reel through or past the translating magnets to a take-up reel. It has been conventional in the past to drive the tape at a point between the two reels by means of a constantly driven drive pulley, the take-up reel being slightly overdriven, with frictional slip, as by means of a slipping belt, to take up the tape as fast as it is supplied from the drive pulley. Certain problems, however, are introduced when it is desired to provide for driving the tape at constant speed in either direction at will, and while these have been solved in various ways in the past, further simplification is desirable.

The primary object of the present invention is therefore the provision of an improved and simplified driving system for the tape of magnetic sound recording machines and the like.

In accordance with the present invention, the usual constant speed tape driving pulley is eliminated and the tape driven by the take-up reel. Since, however, a usual constantly driven take-up reel would move the film faster and faster as it reeled the film up (owing to the gradually increasing circumference of the roll of tape on the take-up reel), the present invention provides a means for compensating the speed of the take-up reel in accordance with the quantity of the tape reeled thereon.

In accordance with the present preferred form of the invention, the required speed compensation is introduced by varying the speed of the electric drive motor. Preferably, there is used for this purpose a drive motor equipped with a governor capable of being mechanically adjusted to vary motor speed while the motor is running, this governor being constantly automatically adjusted in accordance with the varying quantity of the tape on one of the reels.

In a preferred embodiment of the invention, one of the reels is directly and positively coupled to the drive motor, and means are provided for automatically regulating the drive motor governor to vary the speed of the motor inversely with the diameter of the tape on that reel. When that

reel is serving as the take-up reel, it accordingly gradually decreases in speed as the tape roll wound on it increases in diameter, so as to preserve a constant tape speed. Provisions are made whereby the other reel, then serving as the supply reel, simply idles during this time. For the reverse direction of tape drive, the first mentioned reel becomes the supply reel. This reel remains directly coupled to the drive motor, and 10 the speed of the drive motor is again regulated, through its governor, to vary the speed of drive of said reel inversely with the diameter of the roll of tape on the reel. Thus, for the reverse direction of drive of the tape, the reel then serving as the supply reel is positively driven, at 15 gradually increasing speed. At the same time, the reel then serving as the take-up reel is overdriven, through a friction slip clutch, so as to take up the tape as fast as it is supplied from the 20 supply reel. Thus for both directions of tape travel, the quantity of tape on the one reel, which may be called the control reel, governs the speed of the drive motor. For one direction of travel, the tape is taken up by this control reel, 25 while the other idles; for the other direction of travel, the tape is supplied from the control reel, and the other reel is over-driven, with slip, and takes up the tape at whatever speed it is supplied from the control reel. And for both directions 30 of travel, the control reel is driven at a speed inversely proportional to the circumference of the roll of tape thereon, so that the linear speed of the tape between the two reels is substantially constant.

35 Various additional objects, accomplishments and features of advantage will appear and be described in the course of the following detailed description of a present preferred embodiment of the invention, reference for this purpose being directed to the accompanying drawings, in which:

Fig. 1 is a vertical longitudinal section through a magnetic sound recording machine embodying the present invention, Fig. 1 being taken in accordance with line 1—1 of Fig. 2;

Fig. 2 is a section taken as indicated by line 2—2 of Fig. 1;

Fig. 3 is a view taken as indicated by line 3—3 of Fig. 1, the reel-carrying unit at the top of the machine being removed;

Fig. 4 is an enlarged view similar to a portion of Fig. 1, but with the reels and the drive gear for the reels appearing in section;

Fig. 5 is a detail section taken on line 5—5 of 55 Fig. 4;

Fig. 6 is a transverse section taken on line 6—6 of Fig. 4;

Fig. 7 is a transverse section taken on line 7—7 of Fig. 4;

Fig. 8 is a transverse section taken on line 8—8 of Fig. 4;

Fig. 9 is a detail section taken on line 9—9 of Fig. 3;

Fig. 10 is a view taken as indicated by line 10—10 of Fig. 2;

Fig. 11 is a detail section on line 11—11 of Fig. 4;

Fig. 12 is a detail section on line 12—12 of Fig. 2, the cover plate being added;

Fig. 13 is a diagrammatic view of the motor controlling governor; and

Fig. 14 is a diagram of a somewhat simplified but illustrative electrical circuiting arrangement for the machine.

The embodiment of our invention here chosen for illustrative purposes is of a type in which a multiplicity of separate recordings may be made side by side on a single record tape, the several successive recordings being made with the tape travelling first in one direction and then in the other. Such a magnetic sound recording machine is disclosed in United States Letters Patent No. 2,213,631, to Herman S. Heller and Leo G. Butler, dated September 3, 1940, to which reference is directed, and it will be understood that the present invention is concerned not with methods of producing multiple recordings on a single tape, but with means for driving the tape at uniform speed, in either one direction or both directions, whether or not multiple recording is incorporated. Of course, unless successive recordings are to be made with the tape travelling first in one direction and then the other, the provision of uniform tape speed in both directions of travel may not be essential. The present invention is therefore to be understood as providing means for driving the tape at uniform speed in one direction, or in both directions, depending upon requirements.

The illustrated embodiment of the present invention discloses an arrangement in which the reels, translating magnets and tape guides are mounted on a unit which is quickly separable or detachable from the main housing of the machine containing the drive motor, drive gearing, together with necessary amplifier, relays and switches not here illustrated. This feature, which is desirable, though in no way essential to the present invention, is disclosed and claimed in co-pending application of Herman S. Heller, entitled Tape type recording and reproducing machine, filed October 23, 1940, Ser. No. 362,349. The advantage of the arrangement is that it permits interchange of record tapes simply by changing the detachable unit, thus obviating the difficulties and time consumption incident to changing tapes by the usual methods.

Thus, as shown best in Fig. 1, the illustrative machine comprises a main housing 15, having a top plate 16 on which the driving gear is mounted, and a detachable unit 17 mounted on top of housing 15 and resting down on top frame plate 16 of the latter. Detachable unit 17 has a bottom or frame plate 18, preferably provided with apertures 19 which go onto positioning pins 20 extending upwardly from top plate 16 of housing 15, and has a removable cover 21. Preferably, a quickly releasable catch means is provided for detachably securing unit 17 down to main housing 15. Such catch means may typically comprise a strap 24 slidable across the top of the base plate 18

75 of unit 17 and provided with slots 25 adapted to receive catch hooks 26 extending upwardly from top plate 16 of housing 15. Strap 24 is here shown as guided by means of screws 27 mounted in plate 18 and received within longitudinal guide slots 28 in the strap. A spring 29 urges strap 24 to locking position, while an upturned end portion 30 of the strap is adapted to be engaged by a plunger 31 mounted in cover 21 (see Fig. 12), depression 10 of plunger 31 moving strap 24 to disengage from hooks 26.

While not an essential, a feature of great advantage in the illustrative embodiment of the invention is the provision of a co-axial relationship of the two reels, and of the driving members for said reels. This co-axial relationship yields substantial savings in space, and enables the unit to be much more compact than would otherwise be the case. We therefore illustrate and describe one specific embodiment of the invention in which the two reels and the driving gear are embodied in a co-axial design.

The preferred driving gear has a gear housing 41, mounted on the underside of top plate 16 of housing 15, and here shown as comprising an upper housing block 42, a lower housing block 43, and an intervening plate 44, members 42, 43 and 44 being secured in assembly by screws 41a, and being secured to the underside of plate 16 as by screws 16a, as shown in Figs. 3, 4, 6 and 8. The electric drive motor 45 is secured to the bottom of block 43 as by means of screws 46 passing downwardly through block 43 and engaging the motor housing. Motor 45 is mounted with its drive shaft 47 in a vertical position, as indicated in Fig. 8.

In the preferred and illustrative form of the invention, electric drive motor 45 is of a type equipped with a governor such as may be regulated to vary the speed of the motor while the motor is running. A suitable motor equipped with such a governor is manufactured by Bodine Electric Company. The governor, generally designated at 48, and the action of which will be described more particularly hereinafter, is at the bottom end of the motor, as indicated in Fig. 1.

The upper end of motor shaft 47 carries a worm 50 meshing with a worm wheel 51 on a horizontal shaft 52 journaled in housing block 43 (see Fig. 8), and a spiral gear 53 on shaft 52 meshes with a spiral gear 54 that surrounds vertical shaft 55 which extends upwardly into housing block 42, and has at its upper end a disk 56 forming the drive element of an overrunning clutch generally designated at 56a. A bushing 55a set into the bottom of housing block 43 serves as a journal for the lower end of shaft 55, and as a thrust bearing for spiral gear 54. A washer 57 surrounds shaft 55 immediately above spiral gear 54, and is keyed or drivingly connected at the bottom with the top of gear 54 as indicated at 58. The upper side of washer 57 is keyed or drivingly connected, as at 59, with the lower end 65 of a gear sleeve 60 surrounding shaft 55 below clutch disk 56, sleeve 60 being drivingly connected to shaft 55 as by means of transverse connecting pin 61. Sleeve 60 has at the top a spur gear 62, and this gear as well as clutch disk 56 are thus positively driven from motor shaft 47.

Meshing with gear 62 are spur gears 65 (see Figs. 4 and 7) mounted on studs 65a set into housing plate 44, spur gears 65 meshing in turn with an internal gear 66 tightly mounted in the bottom of a sleeve member 67. Extending up-

wardly from the wall 67a at the top of sleeve 67 is a tubular boss 68 which is journaled in a bushing 69 that is mounted in the top of housing block 42 and that extends through an aperture 70 in frame plate 16. Boss 68 has clutch jaws 72 above plate 16, which interengage with clutch teeth 73 formed at the lower end of a tubular boss 74 extending downwardly from reel supporting disk 75. Boss 74 and the portion of boss 68 that projects above plate 16 are rotatable within a bushing 76, which has an intermediate outwardly extending annular flange 77. This flange 77 is received between two annular plates 78 and 79 which surround and support bushing 76, and which are fastened down to plate 18 as by means of screws 80. Disk 75 has an upwardly projecting pin 81, which is adapted to engage in the socket 82 formed in the underside of the central hub 83 of a lower tape reel 84. Hub 83 has a central bore 85 which receives a tubular boss 86 extending upwardly from reel supporting disk 75.

Reel 84 comprises, in addition to the aforementioned hub 83, a pair of suitably spaced side flanges 90, the tape T being rolled onto hub 83 between flanges 90 as indicated.

The aforementioned over-running clutch 56a is of a usual roller ratchet type, the disk 56 at the top of shaft 55 having angular recesses 90 in its periphery receiving spring-pressed rollers 91 adapted to engage the inner periphery of an inverted cup shaped clutch member 92 (Figs. 4 and 6). This member 92 is centrally apertured, as indicated at 93, so as to pass a stud 94 which is screwed upwardly into a shaft 95 that is rotatably received inside tubular member 68. Formed at the lower end of shaft 95 is a friction disk 96, the upper side of which has an annular upwardly facing surface 97 which has bearing against the downwardly facing surface 98 of the wall 67a at the top of sleeve 67. A friction washer 100, formed of felt or the like, is placed between the opposed annular faces formed on disk 96 and on the top of cup shaped clutch member 92, as shown in Fig. 4. A spacer ring 101 seated in disk 56 serves to space member 92 slightly above the upper side of clutch disk 56. The head of stud 94 is received in a cavity 102 sunk in the center of disk 56 (see Fig. 4), and confined between this head and a washer 103 splined on the shank portion of the stud is a compression spring 104. Washer 103 seats against the underside of cup 92, and spring 104 acts to press the member 92 into frictional engagement with friction washer 100. Spring 104 exerts sufficient force on member 92 to permit driving torque to be transmitted from the latter through friction washer 100 to disk 96; however, under certain circumstances later to be explained, slippage may take place at this location.

The upper end of shaft 95 has, above plate 16, a reduced, upwardly extending centering pin 110, and also clutch elements 111 formed at opposite sides of the base of the pin. A reel carrying shaft 112 is rotatively received within tubular boss 74, being journaled in a bearing bushing 113 placed inside the latter, and has a socket 114 adapted to receive centering pin 110, and also clutch elements 115 adapted to interengage with clutch elements 111 on shaft 95 (see Figs. 4 and 5). Shaft 112 is thus drivingly interconnected with shaft 95. The upper end of shaft 112 is formed with an enlarged reel-carrying head 116, having an annular downwardly facing shoulder 117 which bears on bearing washer 118 resting on the upper end of tubular boss 86. Upper reel

120 may be substantially the same as lower reel 84, its hub 121 being centrally bored to receive head 116, as indicated. It has, however, a means for drivingly interconnecting it with head 116. As here shown, this means comprises a locking pin 124 mounted radially in hub 121 and adapted to be projected by spring 125 into locking engagement with longitudinal key-way 126 in head 116.

5 A friction washer 130, typically formed of felt, is placed between the hubs 83 and 121, respectively, of the two reels, the upper face of hub 83 of the lower reel being preferably provided with an annular groove 131 within which said washer is seated. This friction washer 130 serves a purpose which will be explained hereinafter.

10 It will be understood that when the unit 17 is mounted on the unit 15, the driving element 74 for lower reel 84 is clutched to tubular member 68 projecting upwardly through top plate 16 of unit 15, and the driving element 112 for top reel 120 is similarly clutched to drive shaft 95, also projecting upwardly through top plate 16 of unit 15. Cover 21 of unit 17 being removed, lower reel 84 is slipped on over tubular member 86 and driving pin 81 engaged with socket 82, friction washer 130 is then placed in position, and then upper reel 120 is slipped on over head 116 and driving pin 124 engaged with key-way 126. Thus 15 separate transmission means, in the form of concentric, relatively rotatable shaft and sleeve members, are provided between the motor driven shaft 55 and the two reels, these transmission means having disengageable connections which are in driving engagement when the unit 17 is mounted on main housing 15.

20 Inspection of Fig. 2 will reveal that tape T is wound on both reels in the same direction. In the particular arrangement here illustrated, the tape is taken from lower reel 84 around and between a pair of tape tensioning guide pulleys 140 and 141 to a guide element 142 at one end of a translating magnet unit 143. From the other end of magnet unit 143 the tape passes around 25 a similar guide element 144, then travels around and between a pair of tape tensioning guide pulleys 145 and 146, from where it goes on to upper reel 120. The pairs of guide pulleys 140, 141 and 145, 146 are mounted on supports 147 which are 30 pivotally mounted on the bottom plate 18 of unit 17 on pivot axes located between the pulleys. Coil springs 148 surrounding the pivots for the supports 147 exert a torque in a direction to move the pulleys to tension the tape slightly.

35 Translating magnet unit 143 may be of a conventional type, being here shown, however, as comprising a pair of separable insulation blocks 155 and 156, between which is a longitudinal guideway 149 for the tape, and each containing electromagnets 157, and provided with a cover 158. As here shown, the block 156 is slidable on a pair of pins 156a set into block 155, in order that the two blocks 155 and 156 may be separated to permit the tape T to be threaded therebetween. 40 Each magnet 157 may include a wound magnetic core 157a, in which is slidably mounted a pole piece 157b having a tapered tip adapted to engage the surface of the tape T, and lightly pressed against the tape by means of a coil spring 157c mounted in cover 158. Assuming that the machine is designed to produce a multiplicity of consecutive recordings side by side along the length of the tape, with the tape moving in reverse directions as consecutive recordings are 45 made, there will be two magnets spaced longi-

50

55

60

65

70

75

tudinally of the tape for each recording lane, one for recording and reproducing purposes and one for polarizing or record-obliterating purposes, and the tips of the pole pieces of these two magnets may contact the tape only within the limits of the lane of the tape on which they are to operate. Such a system of multiple lane recording is disclosed and claimed in United States Letters Patent No. 2,213,631, to Herman S. Heller and Leo G. Butler, and for a more complete understanding of such a system, reference is directed to said patent, it being sufficient to point out herein that the translating magnet unit 143 is so designed that recordings may be made on the tape with the tape moving in either direction.

The two aforementioned guide elements 142 and 144 at opposite ends of magnet unit 143 are provided with curved guideways 159 conveying the tape in a smooth curve between the spring tensioned guide pulleys and the longitudinal guideway 149 formed between the two magnet blocks 155 and 156. The pair of guide pulleys 140 and 141 is supported in the plane of lower reel 84, and the pair of guide pulleys 145 and 146 will be understood as supported in the plane of upper reel 120. The translating magnet unit 143 is supported in an inclined position, so as to convey the tape between the two reels.

Bearing on the roll of tape on lower reel 84, between reel flanges 80, is a roller 160 carried by the free end of a crank arm 161 that is tightly mounted on the upper end of shaft 162 journaled in a bushing 163 in a tubular member 164 having a flange part 165 secured to plate 18. A coil spring 161a surrounding tubular member 164 and acting between crank arm 161 and flange 165 urges arm 161 toward the roll of tape on reel 84, so as to maintain roller 160 carried by said arm in light pressural engagement with the tape. Bushing 163 and tubular member 164 extend through aperture 166 in plate 18, and a socket 168 extending upwardly into shaft 162 from its lower end receives a centering pin 170 that extends upwardly from a shaft 171 that is mounted for rotation in a supporting block 172 secured to the underside of plate 16. Interengaging clutch elements are formed between shaft 171 and shaft 162; as here shown, the lower end portion of shaft 162 is slotted as indicated at 173 (see Fig. 11), and receives clutch elements 174 formed at the base of centering pin 170. Tightly mounted on shaft 171, and received within a cavity 178 in block 172, is a spiral gear 179, and placed between the bottom of gear 179 and the bottom of cavity 178 is a spring washer 179a which serves as the vertical support for shaft 171.

A lever 180 has bifurcations 181 which straddle block 172 and which are pivotally mounted on pivot pin 182 set in and extending through opposite sides of block 172. The forward end portions of these bifurcations 181 carry studs 185, which project through slots 186 in the sides of block 172 into cavity 178 and engage opposite sides of spiral gear 179 (see Fig. 9). Thus swinging movement of crank arm 161, such as may be caused by change in the diameter of the roll of tape on reel 84, will rotate shaft 162, causing rotation of shaft 171 and gear 179. Such rotation of gear 179 causes studs 185 to be screwed up or down as the case may be, and lever 180 therefore to be moved on its pivot mounting.

The other arm 190 of lever 180 is connected by means of link 191 to one end of a swinging arm 192 which extends transversely across the bottom of the governor, through slots 193 in gov-

ernor housing 194, being pivotally supported on a pin 194 mounted on housing lugs 195. Screw-threadedly mounted in the center of arm 192 is a governor controlling stud 196, which bears 5 against the outer end of a plunger 197 slidable in a guide 198, and which in turn bears against the end of a governor control arm 201 at a point located in line with the axis of rotation of the motor and governor. It may again be mentioned 10 that the governor here shown for illustrative purposes is of a type known in the art, and a detailed description thereof will not be necessary except insofar as to enable the present invention to be understood. A simple diagram (see Fig. 13) 15 will suffice to illustrate the operation of this governor. Governor arm 201 is one arm of a lever 201 pivoted at 208 on a plate or beam 210, the other arm of the lever comprising a centrifugal weight 211. The disposition of the parts is such 20 that as the governor rotates with motor shaft 41, weight 211 tends to move in the direction of the arrow in Fig. 13. Beam 210 is mounted by means of a relatively stiff spring arm 212 on posts such as 213 extending from insulation disk 214, set on 25 the motor shaft, the posts 213 being electrically connected with collector ring 215 mounted on the back of disk 214. When the governor and motor are in rotation, weight 211 tends to move in the direction of the arrow in Fig. 13, as said above, and this causes the weighted lever to tend to pivot on its axis at 208; such pivotal movement is 30 prevented, however, by the end of plunger 197 in engagement with arm 201. The result of centrifugal forces acting on weight 211 accordingly is to move beam 210, on which the weighted lever is mounted, toward disk 214, spring arm 212 yieldingly opposing such action. Beam 210 carries an 35 electrical contact 216, which normally makes with a contact 217 on a conductive support 218 mounted on insulation disk 214 by means of post 218a, and electrically connected via port 218a with inner collector ring 219 on the back of disk 214, as indicated. When beam 210 moves toward disk 214, under the influence of the centrifugal 40 weight 211, contacts 216 and 217 separate, and break the electrical circuit between the two collector rings. The motor has brushes 220 and 221 bearing on collector rings 215 and 219, and such brushes are included in a circuit that energizes 45 the motor as will later be explained.

A spring arm 222 extending from the spring-mounted end of beam 210 engages arm 201 on the side opposite plunger 197.

The speed of rotation at which governor weight 55 211 will generate sufficient centrifugal force to move beam 210 backwardly against spring arm 212 so as to break the electrical energizing circuit of the motor, depends upon the position of plunger 197. For example, if plunger 197 is so positioned that, at zero speed, no pressure is exerted thereby through arm 201 against spring arm 222, then the centrifugal force generated by weight 211 will not become sufficient to deflect beam 210 against the pressure of spring arm 222 until a certain maximum speed of revolution is reached. But now if plunger 197 is advanced 60 against arm 201 so as to deflect spring arm 222 somewhat, then a proportionate part of the supporting power of spring arm 212 is counteracted, and the centrifugal force generated by weight 211 at a lesser speed will be sufficient to deflect beam 210 against the resultant spring pressure then opposing deflection. In this way, the speed of rotation at which beam 210 will deflect against 65 supporting spring arm 212 and thereby open con-

tacts 216, 217, depends upon the axial position of plunger 197, so that by moving plunger 197 by means of stud 198, its carrying arm 192 and link 191, the speed at which the motor cuts out, or has its speed reduced, may be nicely regulated.

Fig. 14 shows a simplified but illustrative wiring circuit for drive motor 45. This motor is here shown as a series wound type, with provisions as indicated at 233 for reversing the field to reverse the direction of motor rotation. Included in one of the current supply leads 230 are the two governor brushes 220 and 221 mentioned in connection with Fig. 13, these brushes being diagrammatically indicated in Fig. 14 as connected to governor contacts 216 and 217, respectively. Preferably, and as here shown, opening of contacts 216, 217 does not entirely open the motor circuit, but simply cuts a resistance in series with the line, so that the impressed voltage is decreased. This has the effect of reducing the motor speed. Accordingly, a resistor 235 and a condenser 236 are shunted across brushes 220 and 221. When the speed of rotation of the motor and governor is sufficient to cause contacts 216 and 217 to become separated, the current supply to the motor is forced to flow through resistor 235, which materially reduces the voltage across the motor and therefore reduces motor speed. Thus each time the motor exceeds the speed for which the governor is set, the contacts 216 and 217 open, and the motor speed thereupon falls. And when this occurs, contacts 216 and 217 again close, causing the motor speed to pick up. The result is that the contacts 216, 217 are more or less constantly opening and closing, and motor speed is held very constant at a speed determined by the setting of the governor. In accordance with the present invention, this governor setting is continuously varied, in such a way that the motor speed is continually varied, but the tape speed is maintained substantially constant.

The operation of the tape driving system of the present invention is as follows: Assume first that the tape is to be driven from top reel 120 to bottom reel 84, the tape travelling as indicated by the arrows in Fig. 2. Motor 45 will at such time be driven in such direction as to cause shaft 55 to rotate in a right-handed direction. Inspection of Fig. 6 will reveal that the over-running clutch at the top of shaft 55 will run free for this direction of rotation, and torque will not be transmitted to upper reel 120, which simply idles at this time. Lower reel 84 is, however, being driven from shaft 55 through spur gear 62, idler gears 65, internal gear 66, sleeve member 67 and the reel supporting member 75 positively clutched to the latter. The friction washer 130 between the two reels exerts a frictional drag on idling upper reel 120 to prevent it from over-running.

At times when the roll of tape on the reel 120 (then acting as supply reel) is larger than the roll of tape on reel 84 (then acting as take-up reel), the reel 120, reel carrying shaft 112 and shaft 95 will of course rotate faster than reel 84, tubular member 14, and sleeve member 67. If shaft 55 and over-running clutch disk 56 turned at the same rate as sleeve 67, power would then be transmitted from shaft 95 through the rollers of the over-running clutch to drive disk 56 and shaft 55. This condition is avoided by gearing sleeve 67 to turn substantially faster at all times than clutch disk 56, in the present instance, in a ratio of approximately 3 to 1. With this provision, disk 56 will always turn faster than shaft 75 of the motor is controlled always by the diam-

5, and clutch member 92 will never catch up with and tend to drive clutch disk 56.

The speed of motor 45 is under the control of the diameter of the roll of tape on lower reel 84. As the roll of tape on reel 84 (then acting as the take-up reel) grows larger and larger, the crank arm 161 carrying roller 160 bearing on the tape on said reel swings gradually outwardly, turning interconnected shafts 162 and 171, and therefore spiral gear 179, in a left-handed direction. This rotation of gear 179 operates through studs 185 to swing lever 180 in a direction to elevate link 191 and pivoted arm 192. Stud 196 carried by arm 192 correspondingly elevates plunger 197, which depresses governor control arm 201 in an upward direction, causing the motor to gradually decrease its speed. Thus as the roll of tape on lower reel 84 grows larger and larger (which with constant speed of drive of the reel would mean greater and greater linear tape speed), the governor of the motor is regulated to give slower and slower motor speed, with the result that the linear speed of the tape is maintained substantially constant throughout the movement of the tape from the upper to the lower reel.

Operation for the reverse direction of tape drive, viz., from lower reel to upper reel, is as follows: Motor 45 drives shaft 55 at such time in a left-handed direction, which causes clutch rollers 91 to drive member 92. Member 92 drives disk 96 through friction washer 100, causing rotation of shaft 112 clutched to shaft 95 and therefore rotation of upper reel 120 mounted on the head 116 of shaft 112. Lower reel 84 is positively driven at such time through the same driving interconnections as for the first described direction of the tape, but of course in the reverse direction of rotation. The speed of drive of motor 45 is again under the control of the diameter of the roll of tape on lower reel 84, roller arm 161 controlling the governor of the motor through the described interconnections to gradually increase tape speed as the diameter of the tape on lower reel 84 grows smaller and smaller. Proper take-up of the tape by upper reel 120 is accomplished by reason of the fact that the upper reel is over-driven, that is, driven at a speed somewhat above that permitted by the speed of the tape as fed from positively driven lower reel 84. In the present illustrative embodiment, this is accomplished by the drive ratios provided between shaft 55 and each of the two reels. Thus as previously described, member 92 driven through the roller ratchet clutch turns at a ratio of one to one with shaft 55, whereas member 67 turns at a ratio of, for instance, 1 to 3 with shaft 55. It will be evident, therefore, that upper reel 120 is over-driven; or driven at a speed faster than will be permitted by the speed of the tape as supplied from lower reel 84. The result is that slippage takes place between friction members 92 and 96, so that reel 120 actually turns at just the speed permitted by the rate of arrival of the tape from lower reel 84, the amount of the over-drive tendency on upper reel 120 being sufficient to assure proper tensioning and proper take-up of the tape.

The linear speed of the tape between upper and lower reels is thus made substantially constant, regardless of the direction of drive, by regulation of the motor speed under the control of the position of the tape on the reels. In the embodiment chosen for illustrative purposes, the speed

eter of the tape on the lower reel, whether the lower reel is functioning as take-up reel or supply reel. When the upper reel functions as supply reel, it simply idles, with friction hold back; when it functions as take-up reel, it is over-driven, with slippage, so as to take up the tape as fast as supplied by the lower reel.

We have now shown and described one present illustrative form which the invention may assume in practice; it is to be understood, however, that this is for illustrative purposes only, and that various changes in design, structure and arrangement may be made without departing from the spirit and scope of the invention or of the appended claims.

We claim:

1. In a drive system for a sound record tape, the combination of two reels, a record tape extending between and wound on said reels, a reversible drive motor positively drivingly connected to one of said reels in a manner to drive said reel in either direction without frictional slip, friction drive means for over-driving the other of said reels from said motor when the tape is travelling in the direction from said one reel to said other reel, said friction drive means slipping sufficiently that said other reel travels at a speed determined by the rate of arrival of the tape from said one reel, and automatic means for regulating the speed of said motor inversely with the quantity of tape reeled on said one reel.

2. In a drive system for a sound record tape, the combination of two reels, a record tape extending between and wound on said reels, a reversible drive motor, positive non-slip driving gear between said motor and one of said reels, driving gear between said motor and the other of said reels including an over-running clutch so arranged as to cause said other reel to be driven only when acting as a take-up reel, said last mentioned driving gear tending to over-drive said reel, a slip driving connection in said last mentioned driving gear, and automatic means for regulating the speed of said motor inversely with the quantity of tape reeled on said one reel.

3. In a drive system for a sound record tape, the combination of two reels, a record tape extending between and wound on said reels, a drive motor, a rotatable shaft adapted to be driven in either direction by said motor, positive non-slip driving gear between said shaft and one of said reels, driving gear between said shaft and the other of said reels, an over-running clutch in the last mentioned driving gear so arranged as to cause said other reel to be driven only when acting as a take-up reel, said last mentioned driving gear being adapted to exert an over-drive tendency on said other reel when acting as a take-up reel, a frictional connection permitting slippage between said shaft and said other reel whereby said other reel will travel at the speed permitted by the rate of arrival of the tape from said one reel, and automatic means for regulating the speed of said motor inversely with the quantity of tape reeled on said one reel.

4. In a drive system for a sound record tape, the combination of two reels, a record tape extending between and wound on said reels, a drive motor, a rotatable shaft adapted to be driven in either direction by said motor, positive non-slip driving gear between said shaft and one of said reels, driving gear between said shaft and the other of said reels, an over-running clutch in the last mentioned driving gear so arranged

as to cause said other reel to be driven only when acting as a take-up reel, said last mentioned driving gear being adapted to exert an over-drive tendency on said other reel when acting as a take-up reel.

5. In a drive system for a sound record tape, the combination of a reversible drive motor, two co-axial relatively rotatable transmission means driven by said motor, one of said transmission means being adapted to transmit a positive drive in either direction of rotation, an over-running clutch and a slip driving connection in the other of said transmission means, co-axial reels adapted to be driven through said transmission means, and a record tape extending between and wound on said reels.

6. In a drive system for a sound record tape, the combination of a reversible drive motor, two co-axial relatively rotatable transmission means driven by said motor, an over-running clutch and a slip driving connection in one of said transmission means, co-axial reels adapted to be driven through said transmission means, a record tape extending between and wound on said reels, and means for regulating the speed of said motor inversely with the quantity of tape reeled on the reel driven by the other transmission means.

7. In a drive system for a sound record tape, the combination of a reversible drive motor, a shaft and a concentric gear driven by said motor, roller ratchet clutch means on the end of said shaft, a clutch member opposed to said clutch means and adapted to be driven therefrom for one direction of rotation of said shaft, a shaft driven by said clutch member, a reel mounted on said shaft, a slip drive connection between the motor and said reel, a rotatable sleeve geared to said gear and surrounding said clutch means and member and a portion of the last mentioned shaft, and a second reel mounted on said sleeve.

8. In a drive system for a sound record tape, the combination of a reversible drive motor, a shaft and a concentric gear driven by said motor, roller ratchet clutch means on the end of said shaft, a clutch member opposed to said clutch means and adapted to be driven therefrom for one direction of rotation of said shaft, a shaft driven by said clutch member, a reel mounted on said shaft, a slip drive connection between the motor and said reel, a rotatable sleeve geared to said gear and surrounding said clutch means and member and a portion of the last mentioned shaft, a second reel mounted on said sleeve, and means for regulating the speed of said motor inversely with the quantity of tape on the last mentioned reel.

9. In a drive system for a sound record tape, the combination of a reversible drive motor, a shaft and a concentric gear driven by said motor, roller ratchet clutch means on the end of said shaft, a clutch member opposed to said clutch means and adapted to be driven therefrom for one direction of rotation of said shaft, a shaft driven by said clutch member, a reel mounted on said shaft, a slip drive connection between the motor and said reel, a rotatable sleeve geared to said gear and surrounding said clutch means and member and a portion of the last mentioned shaft, the gear ratio between said gear and sleeve being such that said gear rotates at substantially lesser speed than the shaft on which said gear is mounted, a second reel mounted on said sleeve, and means for regulating the speed of said motor inversely with the quantity of tape on the last mentioned reel.

10. In a drive system for a sound record tape, the combination of two reels, a record tape extending between and wound on said reels, reversible drive means, positive non-slip drive gearing between said drive means and one of said reels, whereby said one reel is driven in either direction at a speed bearing a fixed constant relation to the speed of the drive means, a driving interconnection between said drive means and the other reel, including a one-way drive clutch so arranged as to cause said other reel to be

10

driven only in a direction to draw tape from said one reel, said driving interconnection being arranged to have an over-drive tendency on said other reel, and a frictional slip clutch in said driving interconnection adapted to slip sufficiently that said other reel is permitted to travel at the speed determined by the rate of arrival of the tape from said one reel.
